UNITED STATES PATENT OFFICE.

BENJAMIN L. CLEVELAND, OF EAST CHATTANOOGA, TENNESSEE.

TIE-PLATE.

1,102,244.

Specification of Letters Patent.

Patented July 7, 1914.

Application filed September 23, 1913. Serial No. 791,435.

To all whom it may concern:

Be it known that I, BENJAMIN L. CLEVELAND, a citizen of the United States, residing at East Chattanooga, in the county of Hamilton and State of Tennessee, have invented certain new and useful Improvements in Tie-Plates; and I do hereby declare the following to be a full, clear, and exact description of the invention, such as will enable others skilled in the art to which it appertains to make and use the same.

This invention relates to new and useful improvements in tie plates and spikes and has for its object the provision of such devices wherein the spreading of railroad rails will be eliminated.

Another object of my invention is the provision of such a device in which the tie may be of any suitable material to which the rail is secured.

A further object of my invention is the provision of such a device which will firmly lock the spike in place and prevent the same from loosening or becoming broken or bent.

Still another object of my invention is the provision of such a device which may be easily and quickly manufactured, cheap to construct and effective in use.

With the above and other objects in view I will now proceed to describe my invention in the following specification and accompanying drawings, in which:

Figure 1 is a longitudinal sectional view of a section of a tie showing my improved device in use. Fig. 2 is a top plan view of the tie plates showing the same as they would appear when assembled. Fig. 3 is a transverse sectional view of one of the plates taken on line 3—3 of Fig. 2, and Fig. 4 is a modified form of my improved tie plate.

Reference being had more particularly to the drawings 1 indicates a tie of the ordinary construction to which the rail, indicated generally by the numeral 2, is adapted to be secured. This rail 2 preferably comprises the head 3, which is formed integral with the web 4, which in turn extends upwardly from the flanges, indicated by the numeral 5.

My improved tie plates, which are illustrated in Figs. 2 and 3, preferably comprise the main body portions 6, having formed integrally therewith the angular extensions 7. To these main body portions and ex-

tending outwardly therefrom at a point opposite the angular extensions 7 I preferably provide the lateral extensions 8 which are preferably of substantially twice the thickness as the main body portion and are adapted to form a trough in which the flange 5 of the rail is adapted to rest. Suitable apertures 9 are formed adjacent the inner edges of the lateral extensions 8 through which the shanks of the spikes are adapted to extend. Adjacent the apertures 9 and extending through the thickness of the lateral extensions 8 I preferably provide the apertures 10 which taper downwardly as clearly illustrated in Fig. 1 and are adapted to receive the ends of the brace members formed on the spikes.

My improved spike which is indicated by the numeral 11 preferably comprises the shank 12 having formed at the upper extremity thereof the head 13. This head extends transversely of the shank and is provided at its rearmost extremity with a suitable downwardly extending member 14 which is preferably pointed, as clearly illustrated in Fig. 1, and is adapted to enter the tie when the device is in place. The opposite end of the transversely extending portion 13 terminates in the flange engaging member 15, as clearly shown. Adjacent the upper end of the shank 12 and immediately beneath the transverse extension 13 I preferably provide the recess 16 which is of sufficient depth to permit the thickness of the plate 8 to lie therein. This recess is provided on the side of the spike through which the angular extension 14 is formed. The side of the spike opposite the recess 16 is preferably provided with a suitable cam face 17 which is adapted to bear against the edge of the rail flange 5 and force the spike rearwardly so that the edge of the lateral extension 8 engages the walls of the recess and prevents the spike from being accidentally removed.

In the modified form of my improved tie plate which is clearly illustrated in Fig. 4, I preferably provide the body portion 18 having formed integral therewith at its edges the laterally extending portions 19 which correspond to the lateral extensions 8 shown in Fig. 2. These laterally extending portions are provided with apertures 20 and 21 through which the spike, previously described is adapted to extend.

It will be apparent from the foregoing de-

scription that when it is desired to make use of my improved device the plates are placed on the tie in a manner illustrated in Fig. 2. The rail is then laid on said plates so that the flange will lie in the trough formed intermediate the lateral extensions 8. It will then be obvious that when the spikes are driven in their respective apertures and into the tie the cam face 17 will engage the rail and force the spike rearwardly and it will be obvious that the rear walls of the apertures 9 formed in the extensions 8 will be forced into engagement with the wall of the recess 16 and the spike will thereby be prevented from becoming accidentally removed. While in the foregoing I have shown and described the preferred embodiment of my invention I wish it to be understood that I may make such changes in the combination and arrangement of parts as will fall within the scope of the claims of my invention.

What is claimed is:—

1. In combination with tie plates comprising body portions, angular extensions formed at the ends thereof, lateral extensions formed on the opposite sides of said body portions, said lateral portions having apertures therein, spikes adapted to extend

through apertures in said plates, said spikes having recesses adjacent their upper ends adapted to receive the end walls of the apertures, and reinforcing means formed integrally with the head of said spikes said reinforcing means being adapted to extend through apertures in the plates and into the tie. 30

2. In a device of the character described plates, extensions formed along the lateral edges of said plates, laterally extending members formed at the opposite edges of said plates, said lateral extensions being of substantially twice the thickness of the plates and having apertures therein, spikes adapted to extend through the apertures, 40 transversely extending heads formed at the upper extremities of the spikes, and reinforcing members formed integrally with the rear extremities of the head, and adapted to extend through the apertures in the plates 45 and into the tie, thereby securing the whole on said tie. 50

In testimony whereof I affix my signature in presence of two witnesses.

BEN. L. CLEVELAND.
